United States Patent Office

Des. 180,340
Patented May 21, 1957

180,340

TOY BANK

Carl F. Peterson, Detroit, and John Berzac, St. Clair Shores, Mich., assignors to Duro Mold and Manufacturing, Inc., Detroit, Mich.

Application August 28, 1956, Serial No. 42,748

Term of patent 14 years

(Cl. D34—11)

Portions of the drawing are dotted to show a stippled finish.

We claim:

The ornamental design for a toy bank, as shown and described.
